UNITED STATES PATENT OFFICE.

CARL MUEHLEISEN, OF BERLIN, GERMANY, ASSIGNOR TO MERGENTHALER LINOTYPE COMPANY, OF BROOKLYN, NEW YORK.

ESCAPEMENT-ACTUATING MECHANISM OF TYPOGRAPHICAL COMPOSING MACHINES.

Application filed September 25, 1926, Serial No. 137,771, and in Germany October 6, 1925.

For effecting the release of matrices from the magazines of typographical composing machines there have been used mechanically actuated means comprising eccentrics or cams located in pivoted yokes, each such eccentric, when the respective key is struck, coming into operative contact with a continuously rotating roller. In such an arrangement the cam yokes perform a swinging movement about their pivot and raises the escapement reeds for effecting the release of the matrices. It has heretofore been proposed to position the cam carrying yokes upon the keyboard frame and render them interchangeable, and for that purpose the yokes are formed with hook-shaped parts engaging with a common pivot rod, the said yokes being held in position by a bar or rails extending over the hook-shaped parts. This arrangement also served for taking up the surplus movement beyond that necessary for effecting a satisfactory matrix release. For this purpose spring pressed pins were provided in the aforesaid bar engaging over the hook-shaped parts, the said pins permitting the hooks to be raised when excess movement occurred.

With such arrangements there was a possibility of individual springs jamming or becoming inoperative.

In the event of this happening it was necessary to remove the whole bar and to substitute the defective springs or pins by others in proper condition. When doing this a number of the other springs and pins would be displaced, so that the re-assemblage of the parts presented considerable difficulty and absorbed a great deal of time.

The present invention overcomes this difficulty by arranging the individual pressure pins so that they may be interchangeably inserted in the bar or rail separately and each independently of all the others.

The drawing illustrates by way of example one constructional form of the invention, and in this drawing:

Figure 1 is a diagrammatic illustration of the releasing mechanism;

Figure 2 is a portion of Figure 1, showing the rail and one of the pressure pins in positions different from those in which they are shown in Figure 1, and

Figure 3 is a detail view of one of the pressure pins and of its spring.

The key lever A formed in the usual man-

ner raises the key rod B when the key button is struck, thus causing a tumbler C to turn about its pivotal axis. The free arm of the tumbler which is located beneath the rear extremity of the cam yoke D, thereby releases the yoke, so as to permit the cam E located in the said yoke, to engage a continuously rotating roller F and to be actuated thereby. This causes the cam yoke D to oscillate about the pivot rod G, so that the rear free end of the yoke D will be raised and cause the escapement reed H also to move upwardly. This reed engages the escapement lever I so as to release the foremost matrix K stored in the magazine and permit said matrix to descend in the known manner into the assembler. The forward extremity of the cam yoke D engaging the pivot rod G, is shaped in the known manner like a hook, so that it straddles the said rod with a capacity of sliding up and down thereon. In order to retain this hook-like extremity in its lowermost position astride the pivot G, pressure pins a are provided, whose lower ends penetrate slots b in a rail or bracket c, which is pivotally mounted on the rod G and is of U-shape or channel form in section. The lower flange of the rail c is formed with slots b previously mentioned, whilst the upper flange e is formed with recesses d open at one side, for receiving the upper portions of the pressure pins a. Each pressure pin is encircled by a spring f whose lower end engages with a lug g on said pin, so as to prevent the spring from accidentally leaving the pressure pin. Each of the pressure pins is also provided with a projection h acting as an abutment against the lower flange of the rail c, and preventing the said pins from penetrating too far through the slots b. The projections or abutments h are located on one side only of the pins and face towards the open side of the rail c, whilst the opposite edges are curved.

By the foregoing means it is possible not only to tilt the rail c from the position shown in Figure 1 to that shown in Figure 2 without relative disturbance of the pins a in said rail, but also to ensure that when the pins are in operative position as in Figure 1, through the one sided pressure exerted between the projections h and the lower flange of the bracket c, the upper ends of said pins shall be pressed against the closed ends of the recesses d to retain the pins in

operative position within the comb-like upper flange *e* of the rail *c*.

The upper flange *e* is further provided with cushions or enlargements *i* which prevent the springs together with the pins from slipping out of the recesses *d*. Each of the pressure pins *a*, serves in known manner, first to permit the removal of the respective cam yoke *D* when the U-shaped rail *c* is tilted over into the position shown in Figure 2 and when all of the cam yokes may be so lifted out, and secondly the pressure pins serve to take up excess movement when for instance the upward limit of movement of the respective escapement reed *H* is reached, the further swinging movement of the cam yoke *D* being about the point of contact of said yoke and reed, the hook-shaped portion thus moving upwards upon the pivot rod *G* and pushing the pressure pin upwardly against the action of its spring *f*.

The subject-matter of the application differs from the arrangements heretofore proposed, which operate in exactly the same manner, by the fact that the pressure pin is shaped not like a round pin but as a flat member which can be manufactured by stamping or such like simple operation. Moreover, and in consequence of the positioning of the pressure pin in the U-shaped rail *c*, the removal and exchange of single pins, in the manner shown in Figure 2, can be easily effected inasmuch as every pin can be removed singly independently of and without disturbing the other pins.

The details of the before described arrangement may be varied within the scope of the invention, inasmuch as the recesses *d* in the upper flange of the bracket *c* may be closed and in such a construction the necessary changes would be made by raising the pressure pins until their lower ends are clear of the slots *b* and free to be removed frontwise. Instead of the rail *c* being of channel shape it may be of any other suitable form as, so far as the invention is concerned, it is only essential that the interchangeability of individual pressure pins be secured through the separate positioning of the same in slots, holes or the like of a common rail. Further than this, the rail *c*, instead of being pivoted in the manner represented could be screwed or otherwise detachably secured in position.

Having described my invention, I declare that what I claim and desire to secure by Letters Patent is:—

1. In escapement-actuating mechanism of a typographical composing machine, the combination with a series of pivoted cam-carrying yokes and a bar movably mounted above the pivots of said yokes, of pins carried by said bar adapted to yieldingly bear upon the cam-carrying yokes and a spring adapted to retain each of said pins in posi-

tion on the bar and in contact with the respective cam-carrying yoke, each pin together with its spring being removable from and replaceable on the bar as an individual unit without disturbing the others when said bar is moved out of its operative position above the yokes. 70

2. In escapement-actuating mechanism, of a typographical composing machine, the combination with a series of pivoted cam-carrying yokes, of a U-shaped bar having its two flanges extending above the pivots of the yokes, the lower flange being slotted and the upper flange formed with open ended recesses, pins supported with their lower and upper portions in the slots and recesses respectively, a spring adapted to maintain the lower end of each pin in contact with a cam yoke, and enlargements at the open ends of the recesses to prevent accidental displacement of the pins from the bar. 80 85

3. In escapement-actuating mechanism of a typographical composing machine, the combination with a series of pivoted cam-carrying yokes and a bar movably mounted above the pivots of said yokes, of pins carried by said bar adapted to yieldingly bear upon the cam-carrying yokes, a spring encircling each pin and adapted to retain the pin on the bar and in contact with the respective cam-carrying yoke, each pin together with its spring being removable from and replaceable on the bar as an individual unit without disturbing the others when the bar is moved out of its operative position above the yokes, and a lug on each pin adapted to be engaged by the encircling spring to prevent accidental detachment of the spring when the pin is removed. 90 95 100

4. In escapement-actuating mechanism of a typographical composing machine, the combination with a series of pivoted cam-carrying yokes, of a U-shaped bar having its two flanges extending above the pivots of the yokes the upper flange being recessed and the lower flange slotted, pins supported with their upper and lower portions in the recesses and slots respectively, a spring adapted to maintain the lower end of each pin in contact with a cam yoke, and an abutment on each pin at one side only adapted to engage the lower flange. 105 110 115

5. In escapement-actuating mechanism of a typographical composing machine, the combination with a series of pivoted cam-carrying yokes, of a U-shaped bar having its two flanges extending above the pivots of the yokes the upper flange being recessed and the lower flange slotted, pins supported with their upper and lower portions in the recesses and slots respectively, a spring encircling each pin and adapted to maintain the lower end of that pin in contact with a cam yoke, a lug on each pin adapted to be engaged by the spring, and an abutment on 120 125 130

each pin adapted to engage the lower flange. 6. In escapement-actuating mechanism of a typographical composing machine, the combination with a series of pivoted cam-carrying yokes, of a U-shaped bar having its two flanges extending above the pivots of the yokes the upper flange being recessed and the lower flange slotted, flat pins supported with their upper and lower portions 5 in the recesses and slots respectively, a spring encircling each pin and adapted to maintain the lower end of the pin in contact with a cam yoke and the upper end of the pin within the respective recess, a lug on one 10 side of each pin adapted to be engaged by the spring and an abutment on the opposite side of each pin adapted to engage the lower flange. 15

7. In escapement-actuating mechanism of a typographical composing machine, the combination with a series of cam-carrying 20

yokes and a common pivot rod for said yokes, of a U-shaped bar pivotally attached to and having its two flanges extending above said rod, the upper flange being recessed and the lower flange slotted, flat pins supported with their upper and lower portions in said recesses and slots respectively, a spring encircling each pin and adapted to maintain the lower end of the pin in contact with a cam yoke and the upper end of the pin within the respective recess, an abutment on one 25 side of each pin adapted to engage the lower flange, a lug on the opposite side of each pin adapted to be engaged by the spring, and a cushion at the open end of each recess adapted to prevent accidental displacement of the upper portion of the respective pin. 30

In testimony whereof I have affixed my signature hereunto.

CARL MUEHLEISEN.
